CLAIM

The ornamental design for a door for a charging unit for an aerosol generating device, as shown and described.

DESCRIPTION

FIG. 1 is a rear, top, and right side perspective view of a first embodiment of a door for a charging unit for an aerosol generating device showing the new design.

FIG. 2 is a front elevational view thereof.

FIG. 3 is a rear elevational view thereof.

FIG. 4 is a top plan view thereof.

FIG. 5 is a bottom plan view thereof.

FIG. 6 is a left side elevational view thereof; and,

FIG. 7 is a right side elevational view thereof.

1 Claim, 7 Drawing Sheets
